UNITED STATES PATENT OFFICE.

GEORGE AMBORN, JR., OF BROOKLYN, NEW YORK, ASSIGNOR TO J. H. WILLIAMS AND COMPANY, OF BROOKLYN, NEW YORK, A CORPORATION OF NEW YORK.

DESIGN FOR A WRENCH.

SPECIFICATION forming part of Design No. 35,385, dated December 3, 1901.

Application filed July 22, 1901. Serial No. 69,341. Term of patent 14 years.

To all whom it may concern:

Be it known that I, GEORGE AMBORN, Jr., residing in the borough of Brooklyn, county of Kings, city and State of New York, have 5 invented a new and original Design for a Wrench, of which the following is a specification.

The new design is shown in the accompanying drawings, in which—

10 Figure 1 is a side view of a wrench embodying and containing the design, and Fig. 2 is a front view thereof.

The new design is embodied in the head part of the wrench.

15 In accordance with the new design the contour of the upper jaw of the head is curved, the curve growing sharper toward the mouth of the wrench-head, which mouth at its upper side is reentrant, extending upwardly at 20 an angle and partly serrated and thence curving downwardly. The lower jaw is in-

clined in the opposite direction to the upper jaw and is also serrated. The head is ornamented by a panel extending in a generally horizontal direction, but inclining downwardly away from the mouth and being bounded by curved lines. A second vertical panel with straight sides and curved ends is beneath the lower jaw.

The essential and characteristic features of 30 the design are the contour of the head and the shape of the mouth.

I claim as my invention—

The design for a wrench shown and described.

35 In witness whereof I have hereunto signed my name in the presence of two subscribing witnesses.

GEORGE AMBORN, JR.
